UNITED STATES PATENT OFFICE.

JACOB DAUTCH, OF BUFFALO, NEW YORK, ASSIGNOR TO SAMUEL S. DAUTCH, OF BUFFALO, NEW YORK.

SEAM-PRESSING AND SMOOTHING DEVICE.

Application filed January 10, 1927. Serial No. 160,162.

This invention relates to tools intended particularly for use by retail shoe dealers and others and has for its object the provision of a novel device by means of which the seam at 5 the back of the counter of a shoe, slipper, pump or the like may be pressed and consequently smoothed down so as to prevent chafing of the foot of the wearer.

It is well known that shoes of all kinds 10 have a seam at the center of the back of the counter and it frequently occurs that this seam is rough or projects into the shoe or beyond the adjacent surfaces, thereby defining a ridge which is likely to cause discomfort to 15 the wearer. I am aware that devices have been designed for pressing or working the counter for the purpose of flexing or softening it but such tools do not operate to smooth 20 the seam itself without affecting the stiffness of the counter itself.

It is with the above facts in view that I have designed the present invention which has for an important object the provision of 25 a device so constructed and arranged as to apply pressure upon the center of the back of the counter of a shoe at the seam for effecting smoothing thereof without necessarily flexing, softening or in anyway distorting the counter and possibly destroying its shape.

30 A more specific object of the invention is to provide a seam pressing or smoothing device constructed in the nature of a clamp having portions to engage against the interior and exterior of the counter at the seam and 35 provided with means for applying substantially as great a degree of pressure as may be desired for flattening the seam.

Another object of the invention is to provide a device of this character in which the 40 shoe engaging portions are so shaped as to conform to the general and natural curvature at the back of the shoe so that the shape thereof will not be altered as a result of the employment of the tool.

45 A further object of the invention is the provision of a tool of this character which is of such construction as to be capable of use in connection with shoes of any and all sizes and types or styles.

50 A still further object is to provide a device of this character which will not mar or otherwise damage the finish and appearance of the shoe upon which it is used.

An additional object is the provision of a 55 device of this character which will be simple

and inexpensive to manufacture, easy to apply, use and subsequently remove, positive in action, efficient and durable in service, and a general improvement in the art.

With the above and other objects and advantages in view, the invention preferably consists in the detailed construction and the arrangement and combination of parts to be hereinafter more fully described and claimed, and illustrated in the accompanying drawing 60 in which:

Figure 1 is a view in side elevation, with parts broken away and in section, showing the device engaged upon the back of a shoe and ready for operation,

70 Figure 2 is a cross sectional view taken on the line 2—2 of Figure 1, and

Figure 3 is a cross section taken on the line 3—3 of Figure 1.

Referring more particularly to the drawing 75 the letter A designates a portion of a shoe having the usual counter B at the center of the back of which is a seam C, as is well known. The entire shoe is not shown as such is unnecessary to a proper understanding of 80 the invention. The number of plies, the thickness of the leather or other shoe material and details as to the lining etc. are not shown or described specifically inasmuch as they have no bearing on the invention itself. 85 The shoe itself is consequently represented in a manner which may be described as somewhat diagrammatic and simply for the purpose of more clearly illustrating the use of the invention.

90 In carrying out the invention I provide a relatively stationary member 10 which is here represented as of substantially inverted U-shape and formed of some suitable metal, preferably by casting. This frame or main 95 member is shown as having channeled sides simply for the purpose of reducing the weight as it is quite evident that it may be of solid construction throughout with flush or plane sides if desired. One leg 11 of this member 100 may have its outer and inner edges or surfaces straight and parallel whereas the other leg 12 has its inner surface 13 curved and convex so as to fit in substantially conforming engagement against the inside of the back of the shoe, as clearly illustrated in Figure 1. All corners are of course preferably rounded off partly for the sake of neatness but principally to avoid leaving sharp corners which would cause discomfort to the operator in 105 110

handling the device. The bight portion 14 of the member 10 has its inner edge or surface formed with a guide rib 15 for a purpose to be described.

5 Located within the open central portion of the member 10 or between the legs 11 and 12 thereof is a clamping plate 16 of curved shape adapted to engage against the exterior of the back of the shoe. The surface 17 of this
10 clamping plate facing toward the surface 13 of the leg 12 is preferably parallel therewith so that when the clamping plate is brought into engagement with the back of the shoe and pressed thereagainst by means to be described
15 there will be no tendency to distort or change the curvature of the shoe counter. In order that the clamping plate 16 may be guided in its movement toward and from the leg 12 of the main member, its upper edge is notched
20 at 18 for sliding engagement along the rib 15.

In order that the member 16 may be moved so that pressure may be applied to the seam at the back of the shoe, I provide a screw 19 threaded through an opening in the leg 11
25 and having one end equipped with a handle 20 and its other end formed with a reduced extension 21 fitting within a recess or socket 22 in the rear or outer side of the clamping plate 16. A washer 23 is preferably mounted on
30 the reduced extension 21 and bears against the rear side of the member 16 and against the shoulder defined by the formation of the reduced end portion 21. The washer acts to a certain extent as a force transmitting member
35 when the screw 19 is turned for advancing the clamping plate toward and into compressing engagement with the shoe.

To provide a suitable connection between the screw and the clamping plate so that the latter may be retracted from engagement with the shoe upon reverse rotation of the screw, I preferably employ a bolt or screw 24 passing through the clamping plate and threaded into the screw 19 axially thereof. The screw
45 24 has its head tapered and countersunk within the member 16 so that the shoe engaging surface thereof will be flush and smooth. To avoid disconnection of the parts at any time during use thereof, I may provide a pin 25 passing transversely through the washer 23, reduced extension 21 and screw 24.

In the operation, the screw 19 is turned to withdraw the plate 16 to its intermediate position so that the device may be engaged with the shoe to be worked upon. The back portion of the counter of the shoe is engaged between the leg 12 and the plate 16, as shown in Figure 1, and the operator then turns the screw 19, by means of the handle 20 so as to
55 advance the plate 16 into engagement with the exterior of the counter. The surface 13 of the leg 12 engages against the seam B to be pressed down or smoothed out. The application of continued pressure results in pressing
60 the seam until it is in an absolutely flat
65

condition. Obviously this will prevent the existence of any annoying ridge at the back of the counter so that chafing of the foot of the wearer will be avoided. The device is removed in the reverse manner as will be obvious. It is really believed that the construction, operation and advantages will be readily apparent to one skilled in the art without further explanation though it might be mentioned that the device has proved to be exceptionally practical. Furthermore there is nothing which will either distort the counter by changing the shape thereof and likewise nothing to mar, scratch or otherwise damage the finish and appearance.

70 While I have shown and described the preferred embodiment of the invention it should be understood that the disclosure is merely an exemplification of the principles involved and that the right is reserved to make all such changes and modifications as will widen the field of utility and increase the adaptability of the device provided such variations constitute no departure from the spirit of the invention or the scope of the claims hereunto appended.

75 Having thus described the invention, I claim:

1. A device of the character described comprising a relatively stationary member
80 adapted to have a portion thereof engaged within a shoe in contact with the seam at the back of the counter, and a relatively movable member located within said first named member and adapted to engage the exterior
85 of the shoe at the back of the counter for applying pressure to the seam and flattening the same.

90 2. A device of the character described comprising a main member having a portion
95 adapted for engagement within a shoe in contact with a seam, a clamping member movably mounted with respect to said first named member and adapted to engage the exterior
100 of the shoe at a point opposite the seam, and means for moving said movable member into compressing engagement with the shoe for flattening the seam, said means comprising a manually operable screw having engagement with said movable member.

105 3. A device of the character described comprising a main member having a portion
110 adapted for engagement within a shoe in contact with a seam, a clamping member movably mounted with respect to said first named member and adapted to engage the exterior
115 of the shoe at a point opposite the seam, means for moving said movable member into compressing engagement with the shoe for flattening the seam, said means comprising a
120 screw threaded through a portion of said main member and engaging the movable member, and means for guiding the movable member in its movement and preventing rotation under the influence of the screw.

4. A device of the character described comprising a main member having a portion adapted for engagement within a shoe in contact with a seam, a clamping member 5 movably mounted with respect to said first named member and adapted to engage the exterior of the shoe at a point opposite the seam, means for moving said movable member into compressing engagement with the 10 shoe for flattening the seam, said means comprising a manually operable screw threaded through a portion of the main member, and means swivelly connecting the screw with said movable member.
- 15 5. A device of the character described comprising a substantially U-shaped member adapted to be straddlingly engaged upon the counter of a shoe at the back thereof and having a portion adapted to engage the seam 20 in the counter, a clamping plate slidably mounted within said U-shaped member and engageable with the exterior of the shoe, and screw means threaded through the U-shaped member and connected with said 25 clamping member for moving the same, the shoe engaging portion of said member and the shoe engaging face of the clamping plate being curved and substantially parallel.
6. A device of the character described comprising a substantially U-shaped member adapted to be straddlingly engaged upon the counter of a shoe at the back thereof and having a portion adapted to engage the seam 30 in the counter, a clamping plate slidably mounted within said U-shaped member and engageable with the exterior of the shoe, and screw means threaded through the U-shaped 35
- member and connected with said clamping member for moving the same, the seam engaging surface of the U-shaped member and the shoe engaging surface of the clamping member being correspondingly curved. 40
7. A device of the character described comprising a substantially U-shaped member adapted to be straddlingly engaged upon the counter of a shoe at the back thereof and having a portion adapted to engage the seam 45 in the counter, a clamping plate slidably mounted within said U-shaped member and engageable with the exterior of the shoe, and screw means threaded through the U-shaped member and connected with said clamping member for moving the same, the seam engaging surface of the U-shaped member and the shoe engaging surface of the clamping 50 member being correspondingly curved, the curvature conforming to the normal curvature of the counter of the shoe. 55
8. A device of the character described comprising a substantially U-shaped member having one leg adapted for insertion within a shoe with its inner surface disposed in contact with the seam at the back of the shoe counter, a guide rib at the bight portion of the U-shaped member, a clamping plate located within the U-shaped member and having a notch slidably engaging said rib, and a screw threaded through the other leg of the U-shaped member and having swivelled connection with said clamping plate, 60 the shoe engaging surfaces being substantially parallel. 65

In testimony whereof I affix my signature.
JACOB DAUTCH.
